UNITED STATES PATENT OFFICE.

JOHN SCHROEDER, OF DAVENPORT, IOWA.

MOTOR.

No. 873,619.

Specification of Letters Patent.

Patented Dec. 10, 1907.

Application filed April 20, 1907, Serial No. 369,261.

To all whom it may concern:

Be it known that I, JOHN SCHROEDER, a citizen of the United States, and a resident of Davenport, in the county of Scott and State 5 of Iowa, have invented a new and Improved Motor, of which the following is a full, clear, and exact description.

This invention has reference to improvements in motors, being more especially de-10 signed as a hydraulic motor but will be found to have a high efficiency when actuated by either steam or air.

The invention has for objects, among others, the provision of a motor of this character which is simple and compact and in which the admission and discharge of the motive agent to and from the cylinder at both sides of the piston, will be controlled by a single positively-operated valve.

20 Reference is to be had to the accompanying drawings forming a part of this specification, in which similar characters of reference indicate corresponding parts in all the figures.

Figure 1 is a side elevation of my improved 25 motor complete; Fig. 2 is a plan of the same; Fig. 3 is a rear end elevation showing the valve casing partly broken away; Fig. 4 is a horizontal, central, sectional view of the cylinder; Fig. 5 is a fragmentary, sectional view 30 of the construction shown at the rear end of Fig. 4, on an enlarged scale; Fig. 6 is a sectional view similar to Fig. 5 but with the controlling valve in a position to admit the motive agent behind the piston, the cylinder at 35 the opposite side of the piston being in communication with the exhaust portion of said valve, and Fig. 7 is a perspective view of the controlling valve removed from the valve casing.

40 My improved motor is carried on a suitable base 1 and includes a cylinder 2 secured near one end thereof, having front and rear heads 3 and 4, respectively, the former being ex-45 tended to provide a chamber 5 communicat- 50 ing with the cylinder, and the latter to form a valve casing 6. Within this casing is ver-55 tically mounted a conical controlling valve 7 shown in detail in Fig. 7. This valve is of the three-way type, comprising an admission port 8 cored out within it for substantially a semi-circumference, where it passes to the exterior of the valves at diametrically opposite points. The port 8 also has an opening 9 through the side of the valve, located in an 55 intermediate position, as clearly shown. Di-

rectly opposite the opening 9 a longitudinal exhaust slot 10 is formed in the valve and extends to the bottom thereof, where it passes into an exhaust pipe 11 connected with the lower end of the valve casing, the 60 valve 7 being cut away at one side adjacent to the lower extremity 12 of the slot 10 to permit the free passage of the exhaust from the slot to the exhaust pipe, a pet cock 11^a leading from the exhaust at one side being 65 preferably provided, as shown in Fig. 3. At one side of the valve casing 6 the actuating supply leads thereinto through a pipe 13 and a pipe 14 leads from the opposite side of the valve casing to the opposite end of the cylinder, discharging into the chamber 5. On top of the casing 6 a cap 15 is bolted or otherwise secured, through which the stem of the valve passes, the latter having fixed thereto a pinion 16 which is in mesh with a rack-bar 70 17 guided in ways, one of which is formed in the cap 15, as best shown in Fig. 2 and the other being formed by a bolt or pin 18 carried by a lug and passing through a slot 19 formed in the rack-bar at the opposite end of the cylinder. A bracket 20 fixed to the rear portion of the cylinder is provided with an overhanging end which receives a bolt 21 threaded into the stem of the valve and is operable to 75 properly adjust the valve in the casing. 85

Slidable within the cylinder is the usual piston 22 having a rod 23 which passes through the chamber 5 and into a crosshead 24 slidably mounted between the guides 25, said guides being rigidly connected together 90 by yokes 26 at opposite ends and secured to the base 1. As best shown in Fig. 4, the end of the chamber receives a packing gland 27 which is forced in the direction of the cylinder by studs 28 and forms a liquid and gas- 95 tight joint about the piston.

Near the opposite end of the base 1 a crank shaft 29 is journaled in suitable bearings, preferably carried by spaced plates 30, the latter being rigidly connected to the base and also 100 connected to each other, as clearly shown. A crank 31 carried by the crank shaft 29 is connected with the crosshead 24 by a connecting rod 32, the connection between this rod and the crosshead preferably being 105 effected by forming the rod with oppositely-disposed trunnions 33 which pass into extended bearings 34 fixed to the crosshead.

Secured to the crank shaft 29 between the plates 30 is a large gear 35 meshing with a 110

somewhat smaller gear 36 fixed to a counter-shaft 37 also journaled in the plates 30. A gear 38 fixed to the countershaft at one side of the gear 36 projects into an opening 39 cut 5 into the base between the plates 30 and meshes with a small gear 40 fixed to a driving shaft 41, this last-named shaft being shown as carrying the usual fly-wheel 42.

The crank 31 is extended at one side to 10 form an auxiliary crank 43, the arm of which is slotted to adjustably receive a crank pin 44, the latter being connected with a valve-rod 45 which is provided with a flattened and slotted rear end through which passes a bolt 15 or other projection 46, this last-named bolt being adjustably secured in any suitable manner to the rack bar 17. At each end of the slot of the valve rod a stop 48 is adjustably connected by a bolt 49, said stops projecting into the path of the bolt 46 and operating to slide the rack-bar 17 to oscillate the controlling valve in the proper sequence with the reciprocation of the engine piston. It is apparent from this construction by the 25 adjustment of the stops 48 and the pin or bolt 49, that the amount of oscillation of the controlling valve as well as its position at different periods of the piston travel, may be regulated.

30 In the operation of the motor, when the piston and controlling valve are in the position as illustrated in Fig. 4, the actuating agent passes into the valve casing and through the port 8 in the valve to and 35 through the pipe 14 which discharges into the chamber 5 and thence into the cylinder at the front of the piston, causing the latter to travel rearwardly. As the limit of movement of the piston in this direction is approached, the valve rod 45 through the intermediate connecting mechanism, revolves the controlling valve substantially a semi-revolution, thereby placing the forward portion of the cylinder in communication with the 40 exhaust slot 10 of the valve and the cylinder at the rear of the piston in direct communication with the actuating agent through the port 8, causing the piston to again move forward, as shown in Fig. 6. As the piston 45 reaches the forward limit of its stroke, the controlling valve is again shifted to the position shown in Fig. 4, placing the rear portion of the cylinder in communication with the exhaust and the forward portion thereof in 50 communication with the supply port in the controlling valve. This continuous operation of the piston drives the driving shaft from the countershaft through the intermediate gearing at slow speed, which admits of 60 the operation of the motor under low pressure motive agents.

The invention has been described in detail in order that the construction and operation might be clearly understood. I, however, 65 regard the precise construction as not mate-

rial and consider that I am entitled to such changes as fall within the scope of the claims annexed.

Having thus described my invention I claim as new and desire to secure by Letters Patent:

1. In a motor, the combination of a cylinder having a piston, a driving shaft driven by said piston, a valve controlling the admission and the exhaust to the cylinder at 75 each side of the piston, a pinion fixed to the valve, a rack bar slidably mounted in a guideway arranged longitudinally of the cylinder, in mesh with the pinion, and means 80 slidable relatively to the rack-bar for operating it from said shaft.

2. In a motor, the combination of a cylinder having a piston, a rotary valve for controlling the admission and the exhaust to the cylinder, reciprocating means for oscillating 85 said valve including a rack bar, and adjustable stops carried by said reciprocating means acting on said bar for regulating said oscillations.

3. In a motor, the combination of a cylinder 90 having a piston, a crank shaft driven by the piston, a rotary valve for regulating the admission and exhaust to the cylinder, a pinion fixed to said valve, a rack-bar in mesh with said pinion and having a projecting 95 member, a slotted rod connected to said crank shaft and slidable on said member, and adjustable stops carried by said rod in the path of and at opposite sides of said member.

4. In a motor, the combination of a cylinder having a piston, a valve casing communicating with said cylinder at opposite sides of the piston, a three-way valve revolvably mounted in the casing, a pinion fixed to 105 the valve, a rack bar in mesh with the pinion, and means having a sliding connection with the rack bar for reciprocating it to oscillate the valve in proper sequence with the operation of the piston.

5. In a motor, the combination of a cylinder having a piston, a valve casing communicating with the cylinder, a valve vertically and revolvably mounted in said casing, means for revolving the valve in proper sequence with the reciprocations of the piston, a bracket overhanging the valve casing, and a screw supported by said bracket and threaded into said valve for adjusting it longitudinally of the casing.

6. In a motor, the combination of a cylinder having a piston, a valve casing communicating with the cylinder at opposite sides of the piston, a cylindrical valve revolvably mounted in the casing having admission openings and a discharge opening, a pinion fixed to said valve, means carried by said cylinder for adjusting the valve in the casing, a rack-bar in mesh with the pinion, and means for reciprocating the rack-bar to 125 130

oscillate the valve in proper sequence with the reciprocations of the piston.

7. In a motor, the combination of a cylinder having a head provided with a valve casing which communicates with the cylinder, a three-way valve revolvably mounted in the casing, a pinion fixed to said valve, a rack-bar in mesh with the pinion and having a projecting member, a piston operable within the cylinder, a crank shaft driven from the piston, a rod connected with the crank shaft

and having a slotted end slidable upon said member, and an adjustable stop in the path of and at each side of said member carried by said rod.

In testimony whereof I have signed my name to this specification in the presence of two subscribing witnesses.

JOHN SCHROEDER.
